UNITED STATES PATENT OFFICE.

WILLIAM A. BOCK, OF CHICAGO, ILLINOIS.

SWITCH-STAND.

SPECIFICATION forming part of Letters Patent No. 447,424, dated March 3, 1891.

Application filed November 19, 1890. Serial No. 371,925. (No model.)

To all whom it may concern:

Be it known that I, WILLIAM A. BOCK, a citizen of the United States, residing in Chicago, in the county of Cook, in the State of Illinois, have invented certain new and useful Improvements in Switch-Stands, of which the following is a specification.

My invention relates to the class of switch-stands known as "automatic," which are thrown by the passage of the train through the switch, if the latter should be wrongly set.

The stand herein shown and described is an improvement upon that patented to me by the United States, No. 437,966, dated October 15, 1890.

The object of my invention is to provide for the more thorough protection of the working parts both from accidental injury and from clogging. The yielding clutch, which is operated by the passage of the train, is constructed somewhat differently from that shown in my former patent above named, as will appear from the description which follows.

In the accompanying drawings, Figure 1 is a side elevation of my switch-stand. Fig. 2 is a vertical section of the same, the point of view being at right angles to that of Fig. 1. Fig. 3 is a horizontal section on line 3 3, Fig. 2. Figs. 4, 5, and 6 illustrate details hereinafter described.

A is the frame or body of the stand, through which passes the shaft B, having at its lower end the crank C, the latter being connected by the rod D to the switch. To the shaft B is keyed a block E, which block has a cavity whose opposite sides *e e* are parallel. Said cavity extends through the side of the block E. On the top of the stand A is fitted a cap F. From its upper side rises a square or polygonal projection or boss f, and its lower side has a sleeve f', the upper portion of which is made to fit the bearings in the block G, said block being keyed or otherwise fastened in the top of the stand A. The lower part of the sleeve f' is squared or furnished with a feather, so that the sliding clutch-block H fitted thereto is free to move longitudinally of the sleeve f', but cannot revolve upon it. The lower face of the block G and the upper face of the block H are made so as to form a yielding lock with each other, the spring I

keeping them in contact, as shown in the drawings.

The locking-faces, as shown herein, (*vide* Figs. 2 and 6,) are pyramidal, as described in my patent before named, as I prefer to employ this form; but it is not essential to the invention herein described that these faces should be so formed.

The upper end of the boss f is made circular, as indicated in Fig. 2, so as to fit the corresponding cavity in the block E.

Fig. 5 shows a longitudinal section of the cap F and its upper and lower extensions. The projection f of the cap is of such size that its diameter measured across its diagonal is equal to or slightly less than the distance between the parallel faces *e e* of the cavity within the block E, so that the block E and its attached shaft can revolve independently of the cap F. To lock the block E and the cap F together, I employ a forked lever whose construction is shown in Figs. 2 and 4. Said lever J is pivoted to the block E, as is also the lever shown in my prior patent; but instead of being made in a single piece, as therein described, the forked portion J of the lever, which embraces the polygonal head of the cap F, is pivoted to the hand portion J'. The forked portion j of the lever is best seen in Fig. 4. The fork fits between the parallel sides *e e* of the block E and the sides of boss f. (*Vide* Fig. 3.) When the parts are in the position shown in Fig. 3 and in full lines in Fig. 2, the block E and the cap F are locked together. When the hand-lever is raised to the position shown in the dotted line, the forked portion j is withdrawn from between the boss f and the sides of the cavity within the block E, so that the block is free to revolve independently of the cap F. The inner ends of the fork of the part j are provided with hooks h h, which, by catching upon the depending lip i of the block E, prevent the entire withdrawal of the fork. (*Vide* Figs. 2 and 4.) At a is provided an eye for the insertion of a lock by which the withdrawal of the lever J may be prevented. The operation of the yielding clutch formed by the clutch-block G and H is described in my former patent. The pressure upon the crank C, tending to be caused by the passage of the train

and tending to rotate the switch-shaft B, will, if sufficient, cause the spring I to be depressed by the action of the sliding clutch-faces upon the block H. The rotation of the shaft, block 5 E, and cap F, together with the clutch-block H, will thus be effected.

I claim—

1. The combination, in a switch-stand, of a block secured to a shaft, by which the shaft 10 is thrown, said block having a cavity with parallel sides, the cap fitted to the body of said switch-stand so as to be capable of rotating therein, and provided with a yielding clutch, and having a polygonal boss extending 15 within the cavity of said block, and a forked lever fitted within said cavity and over said polygonal boss, whereby said block and cap may be locked together or may, by the withdrawal of said forked lever, be released 20 from each other, substantially as described.

2. In a switch-stand, the combination of a frame, a shaft revoluble therein and adapted to operate the switch, a block secured to said shaft and having a cavity two of whose sides 25 are parallel, a hand-lever having a forked portion fitted within said cavity, a cap interposed between said block and said frame and extending within the cavity of said block and having the top of the polygonal section over 30 which the forked end of said lever fits, substantially as described.

3. The combination, in a switch-stand, of a frame, a shaft revoluble therein and adapted to operate the switch, a cap fitted to said frame 35 and surrounding said shaft, a device adapted to lock said cap to said shaft, a clutch-block secured to said frame, and a sleeve formed upon or attached to said cap, having a yielding clutch-block adapted to engage with the 40 first-named clutch-block and to slide upon said sleeve, but not to revolve thereon, and a

spring maintaining the contact between said fixed and said yielding clutch-block, substantially as described.

4. The combination, in a switch-stand, of 45 a frame and a shaft revoluble in said frame and adapted to operate the switch, a block secured to said shaft and having a cavity therein whose two opposite sides are parallel, a hand-lever having a forked end fitted within 50 the parallel sides of said cavity, a cap interposed between said block and frame, having a polygonal boss extending within said cavity, said polygonal boss being fitted to the forked end of said lever, a sleeve extending below 55 said cap and forming a part thereof or attached thereto, said sleeve being adapted to revolve within the stand and having a yielding clutch-block fitted to slide longitudinally thereon and revolve therewith, a fixed clutch-block adapted to engage with said yielding clutch-block, and a spring for maintaining contact between said clutch-block, substantially as described.

5. The combination, in a switch-stand, of 60 a yielding lock comprising a fixed clutch-block fitted to the frame of the switch-stand, a sleeve extending through said clutch-block so as to be capable of revolution therein, a shaft adapted to operate the switch passing through 65 said sleeve, and having devices adapted to lock it to and release it from said sleeve, a yielding clutch-block fitted to said sleeve so as to be capable of sliding longitudinally of 70 said sleeve, but not to revolve thereon, and a spring for maintaining contact between said fixed and said yielding clutch-block, substantially as described.

WILLIAM A. BOCK.
